UNITED STATES PATENT OFFICE.

GEORGE H. BACKMIRE, OF COLLEGEVILLE, PENNSYLVANIA.

FUME ARRESTER.

Application filed January 24, 1924. Serial No. 688,161.

To all whom it may concern:

Be it known that I, GEORGE H. BACKMIRE, a citizen of the United States, residing at Third Avenue and East Street, Collegeville, 5 in the county of Montgomery and State of Pennsylvania, have invented new and useful Improvements in Fume Arresters, of which the following is a specification.

My invention relates to a new and useful improvement in fume arresters, and has for its object to so construct a device of this description that it may be readily attached to a gas range or other such device in a convenient and effective manner regardless of 15 the size or shape of the flue opening or collar around the same.

Another object of my invention is to provide in combination with the fume arrester a suitable adapter which may be readily 20 attached to different sized gas range flues whereby the fume arrester is made to fit any 25 gas range or other like device.

A further object of my invention is to make the device in three principal sections 25 providing for the proper fitting of the joints of the sections.

A still further object of my invention is to so construct the support for an inverted glass that the cage wires may be readily secured thereto, and the tray for holding the sand or other absorbent material made a 30 permanent part thereof to facilitate the insertion of the support and tray when it is necessary to clean the same.

With these ends in view, this invention 35 consists in the details of construction and combination of elements hereinafter set forth and then specifically designated by the claims.

In order that those skilled in the art to 40 which this invention appertains, may understand how to make and use the same, I will describe its construction in detail, referring by numerals to the accompanying drawings 45 forming a part of this application in which:—

Fig. 1, is a vertical sectional elevation of 50 my improvement showing the same attached over the outlet flue of a gas range.

Fig. 2, is a bottom plan view of the adapter with the clamp removed.

Fig. 3, is a section taken at the line 3—3 of Fig. 2, with the clamp rod in position.

Fig. 4, is a top plan view of the adapter base per se. 55

Fig. 5, is a central sectional view of the support element carrying the tray.

Fig. 6, is a plan view of Fig. 5. 60

Fig. 7, is an enlarged detail view of the clamping end of the clamp rod.

Fig. 8, is a detail view of the bushing through which the clamp rod passes.

Fig. 9, is an edge view of said bushing.

Fig. 10, is a view similar to Fig. 1 showing a modification of my invention adapted 65 to be made of sheet metal.

Fig. 11, is a plan view of the cage shown in Fig. 10.

Fig. 12, is a plan view, on a reduced scale, 70 of another form of the adapter.

Fig. 13, is a side elevation thereof showing a portion of the arrester in section connected therewith.

Fig. 14, is a section at the line 14—14 of Fig. 12. 75

Fig. 15, is a section at the line 15—15 of Fig. 14.

In carrying out my invention as here embodied, 1 represents a portion of a gas range or the like having the outlet flue 2 surrounded by a collar 3 over which the adapter for the fume arrester is to be placed. 4 represents the adapter which, as shown in Figs. 1 to 10, consists of a semi-spherical base having a cylindrical flange or collar 5 formed therewith and this base is of sufficient size to be placed over and inclose the flue opening of any standard make of gas range; that is to say it is of greater diameter at its base than the largest standard flue outlet of the ordinary gas range. Around the lower edge of the adapter is secured by cement or otherwise an asbestos gasket 6 so that when the adapter is placed upon the upper surface of the range as 95 shown in Fig. 1, a packed joint will be provided.

7 represents a rod extending across the adapter, one end of which is threaded as at 8 while the opposite end extends through an unthreaded opening in the boss 9; this arrangement is for convenience in assem-

bling. Upon the rod 7 is slidably mounted the prongs 10, through the hubs of which are threaded the screws 11 and by means of the latter these prongs are held in any adjustment upon the rod; and between the hubs of these prongs is interposed a coil spring 12 the purpose of which latter is to force the prongs outward in firm contact against the collar 3 when the screws 11 are released.

13 represents an extension formed with the flange 5 and in the inner end of this extension is formed an open slot 14 for the reception of the clamp rod 15, and in practice I provide a bushing 16 preferably made of a piece of wire so bent as to form an eye 17, through which the clamp rod 15 may pass, and also to provide downwardly projecting ends 18 adapted to fit within the open end of the slot 14. By this arrangement when the clamp rod is in place the bushing will serve as a washer upon which the thumb nut 19 may bear when said nut is screwed downwardly upon the threaded end of said rod.

25 The lower portion of the clamp rod 15 is bent at right angles and terminates in a loop 20 which serves as a shoe to bear against the underside of the gas range top 1 as clearly shown in Fig. 1. When this rod is in place and the thumb nut set up it will firmly hold the device in place upon the gas range, the shoe being prevented from slipping backward out of engagement by the vertical portion of the rod contacting with the spring 12 or the rod 7 upon which said spring is coiled.

21 represents a reducing pipe which is tapered upward and has a straight section 22 adapted to fit within the collar 5 and 40 also provided with a flange 23 for resting upon the upper edge of said collar to make a joint at this point.

24 represents a support which is in the form of a short pipe and serves as a support for the cage 25 and an inverted glass to be placed over said cage; and for this purpose the lugs 26 are formed with the support, through which lugs the lower ends of the wires of the cage pass and may be secured 50 therein by riveting or otherwise, as clearly shown in Fig. 1. Around this support is placed the tray or cup 27 which is preferably of sheet metal having a straight tubular section 28 fitted tightly over the lower portion of this support, said tray being flared upward so as to make a convenient holder for any suitable absorbent material, such as sand, ashes or cotton.

From the foregoing description the application of my invention will be obviously as follows:—

The prongs 10 are moved toward each other as close as will be permitted by the spring 12 and then set in position by screwing down upon the screws 11. The adapter

is set over the flue opening 2 and the screws 11 backed off so as to permit the prongs to be forced outward by the spring 12 into firm contact with the collar 3. This will centralize and hold the device in position temporarily until the clamp rod 15 is inserted within the open end slot 14 and the shoe placed beneath the top 1 of the gas range when by screwing the thumb nut 19 downward into firm contact with the bushing 16 the device 75 will be permanently locked in place. The tray 27 may be then filled with sand, or other suitable material, and a glass, such as a drinking glass, inverted over the cage 25 and caused to rest upon the lugs 26 of the support 24; it being understood that a suitable absorbent material such as raw cotton is placed upon the wires of the cage for arresting certain objectionable matter which would otherwise pass off as fumes 85 from the gas range.

The form of my invention above described is especially designed for making the adapter, reducing pipe and support of cast iron while the modified form shown in 90 Figs. 10 and 11 is especially adapted for making these parts of sheet metal, the construction being as follows:—

The adapter 44 in this modification instead of being semi-spherical has its lower 95 portion of cylindrical shape while the upper portion thereof is in the general form of a truncated cone with which is formed the short pipe 55. The lower end of the reducing pipe 121 is adapted to fit over the short 100 pipe 55 while the upper portion of this reducing pipe serves to receive and support the cage 120.

A bead 56 is preferably formed around the reducing pipe in order that the tubular 105 section 28 of the tray 27, when passed over the upper portion of the reducing pipe, may be limited in its downward movement by said head thus facilitating the assembling of the device.

9885 9890 9895 9900 9905 9910 9915 9920 9925 9930 9935 9940 9945 9950 9955 9960 9965 9970 9975 9980 9985 9990 9995 9999

is set over the flue opening 2 and the screws 11 backed off so as to permit the prongs to be forced outward by the spring 12 into firm contact with the collar 3. This will centralize and hold the device in position temporarily until the clamp rod 15 is inserted within the open end slot 14 and the shoe placed beneath the top 1 of the gas range when by screwing the thumb nut 19 downward into firm contact with the bushing 16 the device 75 will be permanently locked in place. The tray 27 may be then filled with sand, or other suitable material, and a glass, such as a drinking glass, inverted over the cage 25 and caused to rest upon the lugs 26 of the support 24

termining the position of the adapter upon the gas range and preventing any sidewise movement thereof. The clamp rod 15 serves to hold the device against vertical displacement in the same manner as before described.

The cage 120 adapted to this modified construction consists of the wires 125 which cross each other at the top and extend downward at right angles and are coiled around the ring 126 thereafter extending horizontally outward forming the supports 124 their ends being clamped around the ring 127. This makes it possible to readily apply the cage to the device or remove the same therefrom thus facilitating the shipping and assembling of the device.

In the formation illustrated in Figs. 12 to 15 inclusive, 144 represents the adapter including a flat base 145 having a sheet of asbestos 146 disposed across its under face and provided with an upwardly projecting collar or flange 147. These parts are preferably of oval shape although I am not limited to any specific configuration. An extension 148 is formed with the collar 147 similar to the extension 13 and for the same purpose.

A rod 149 extends across the adapter with its end fixed in the collar 147 and on this rod, preferably midway its length, is secured a pendant 150 having an elongated opening 151 therethrough in which are slidably mounted the shanks 152 of the gripping prongs 153 and said shanks are preferably of polygonal cross section to prevent rotation of the gripping prongs. In the lower end of the pendant is threaded a screw 154 which projects into the opening 151 for engagement with the shanks of the gripping prongs to force them together and against the top wall of the elongated opening to bind them in any adjusted position as will be obvious.

In the use of this form of the device the screw 154 is released from the shanks of the gripping prongs 153 and the latter adjusted so that their outer free ends engage the inner surface of the gas range collar 3 after which the screw 154 may again be screwed home to hold the prongs in their adjusted positions. The coaction of the gripping prongs with the range collar will properly position the adapter after which the clamp rod may be attached in the same manner as before described and the fume arrester then mounted on the adapter.

Of course I do not wish to be limited to the exact details of construction as herein shown as these may be varied within the limits of the appended claims without departing from the spirit of my invention.

Having thus fully described my invention, what I claim as new and useful is:—

1. A fume arrester comprising an adapter of sufficient dimensions to set over and in-

close an outlet flue of a gas range, means for locating and temporarily holding the device in place upon the gas range, and means for clamping the device in final position.

70

2. In a device of the character described, an adapter of sufficient dimensions to set over and inclose various sized flue outlets of gas ranges, a packing gasket being adapted to contact with the upper surface 75 of the gas range, a rod extending crosswise of the adapter, two prongs slidably mounted upon said rod, a spring interposed between said prongs, means for holding said prongs upon the rod against the action of said 80 spring and permitting the release of said prongs, said prongs being adapted to center the adapter and temporarily hold it in position, an angular clamp rod having a 85 shoe formed upon one end thereof for contacting with the underside of the top of a gas range, and means for clamping and holding said rod in position to firmly hold the adapter in position.

3. In a device of the character described, 90 an adapter of sufficient dimensions as to set over and inclose various sized flue outlets of gas ranges, a packing gasket positioned around the lower edge of said adapter, said gasket being adapted to contact with the 95 upper surface of the gas range, a rod extending crosswise of the adapter, two prongs slidably mounted upon said rod, a spring interposed between said prongs, means for holding said prongs upon the rod against the action of said spring and permitting the release of said prongs, said prongs being adapted to center the adapter and temporarily hold it in position, an angular 100 clamp rod having a shoe formed upon one end thereof for contacting with the under side of the top of a gas range, means for clamping and holding said rod in position to firmly hold the adapter in position, a 105 reducing pipe adapted to be coupled to the adapter, a support, an upwardly flared tray carried by said support, the lower end of said support and tray passing within the upper end of the reducing pipe, lugs formed with the support and cage wires secured to 115 said lugs.

4. A fume arrester comprising an adapter having a collar formed therewith, a reducing pipe, the lower end of which fits snugly within said collar, a support the lower end of which fits within the upper end of the reducing pipe, lugs formed with the upper end of the support, cage wires secured to 120 said lugs, and an upwardly flared tray, the lower portion of which is tightly fitted upon the lower portion of said support.

5. A fume arrester comprising in combination a semi-spherical adapter, a compressible gasket secured over the lower edge 125 of said adapter, a rod passing horizontally 130

- through the adapter, one end of said rod being threaded into one wall of the adapter, two prongs each having a hub adapted to slide upon said rod, a spring interposed between said hubs, screws threaded in the hubs in such manner as to bear against the rod to hold the prongs against the outward thrust of the spring until it is desired to release said prongs for centering said device
- 5 over a gas range outlet flue, a collar formed with the adapter, an extension formed with the collar, said extension having an open end slot therein, a bushing the ends of which are adapted to fit within said slot, an
- 10 angular clamping rod one end of which passes through said slot and bushing and a thumb nut threaded upon the upper end of said rod for drawing the latter into its clamping position.
- 15 6. A fume arrester comprising an adapter, a collar cast with said adapter, a reducing pipe having a straight section adapted to fit within said collar, a flange cast with the reducing pipe adapted to seat upon the
- 20 upper edge of the collar and a support
- 25 carrying a tray, the lower portion of said support and tray passing into the upper end of the reducing pipe.
7. A fume arrester comprising an adapter of sufficient diameter to inclose the outlet flue of a gas range, means for determining the position of said arrester relative to said flue, means for clamping said arrester upon the range, a reducing pipe removably connected with the adapter, a tray fitted around the upper portion of the reducing pipe, a cage adapted to fit over the upper end of said reducing pipe, and support wires projecting over the base of said cage.
8. In a fume arrester, an adapter including a base, a collar projecting therefrom, a rod disposed across the interior of said collar, prongs supported by said rod and adjustable to change their relation to each other and means to hold the prongs in different adjusted positions.
- 40 In testimony whereof, I have hereunto affixed my signature.

GEORGE H. BACKMIRE.
